UNITED STATES PATENT OFFICE.

LOUIS SMITH, OF CHICAGO, ILLINOIS, ASSIGNOR OF ONE-HALF TO
CHARLES A. AMBRUSTER, OF CHICAGO, ILLINOIS.

CHECK-MARKER.

No. 819,318.

Specification of Letters Patent.

Patented May 1, 1906.

Application filed August 12, 1904. Serial No. 220,529.

To all whom it may concern:

Be it known that I, LOUIS SMITH, a citizen of the United States, residing at Chicago, in the county of Cook and State of Illinois, have 5 invented certain new and useful Improvements in Check-Markers; and I do hereby declare that the following is a full, clear, and exact description thereof, reference being had to the accompanying drawings, and to 10 the letters of reference marked thereon, which form a part of this specification.

This invention relates to certain new and useful improvements in devices for preventing the fraudulent raising of checks, drafts, 15 and like documents, and more especially to that class of devices embodying a plurality of character disks or wheels located side by side and independently rotatable on a common shaft and provided on their peripheries 20 with a plurality of number and character types which are designed to be severally brought to a common printing-line by independent rotation of the disks on their axes, against which the check or other document 25 to be marked is pressed by a suitable platen to imprint the set-up combination of numbers or characters on the check or the like.

Among the objects of my invention is to 30 simplify the construction of devices of this character and to facilitate the operation of rotating the printing-wheels to bring the characters thereof to the printing-line.

Other objects of the invention will appear 35 from the following description.

The invention consists in the matters hereinafter set forth, and more particularly pointed out in the appended claims.

In the drawings, Figure 1 is a front elevation, with parts broken away, of a check-marking device made in accordance with my 40 invention. Fig. 2 is a horizontal section taken on line 2 2 of Fig. 1. Fig. 3 is a side elevation with parts removed to show the interior construction and with other parts 45 shown in section. Fig. 4 is a transverse vertical section taken on line 4 4 of Fig. 3.

As shown in the drawings, A designates the supporting-base of the device, which is integrally formed with an upwardly-curved 50 shank A', which latter terminates at its upper end in a guide-head A² for the vertically-reciprocating plunger of a platen herein-after to be described. The curved shank A'

is made sufficiently wide to constitute the back wall of a chamber formed to receive the 55 printing-wheels, of which chamber B B designate the side walls or plates, C the front wall, and D the top wall thereof, which latter is made flat and horizontal. Extending between and affixed to the side plates or walls 60 of said chamber is a non-rotative shaft E, upon which are loosely mounted a plurality of printing-wheels F, herein shown as six in number, and each freely rotative on said shaft independently of the others. Said 65 printing-wheels are provided on a portion of their peripheries with type characters f f. Said wheels are made of sufficient diameter relatively to the chamber in which they are located to extend slightly above the level of 70 the top plate D of the chamber, the said top plate D being provided with a transverse slot d (shown best in Figs. 2 and 4) to permit the types at the tops of the disks to project therethrough in proper register to constitute 75 the printing-line. Between one of the wheels F and the side plates B is located a spacing-washer f', which separates said disk or wheel from said side plate and minimizes the friction between the moving disk and station- 80 ary plate.

Each of the disks F is provided on its side face with a rigidly-secured concentric pinion f², said pinions rotating with their respective disks freely on the shaft E, and said pinions 85 coöperate with suitable gear-levers by which the disks are rotated. The pinions f² are made thin and of small diameter and act as separators for the disks, and the levers which coöperate with the pinions are also thin, being herein shown as substantially the same thickness as the pinions, or perhaps slightly thinner.

The form of lever herein shown is designated as a whole by the reference-letter G, 95 and are each made from a flat sheet-metal plate, and comprises a generally triangular body the smaller end of which is loosely pivoted to a transverse shaft H, located at the rear of the disk-chamber. Said levers are 100 each provided with a narrower handle portion G², which extends through slots c in the curved front plate C of the chamber. Said handle portions are provided at their forward ends with knobs g g, by which they may be 105 readily engaged by the hand or finger of the

operator to swing the same. Said levers are provided between the shaft H and the handles thereof with curved slots G³ concentric with the axis of the shaft H, each made wide enough to receive the adjacent gear-pinion f² of the associated disk F. Each lever is provided at one of the margins of the curved slot thereof with a curved rack or set of teeth g', adapted to mesh with the associated pinion f². By reason of the fact that said pinions f² are made much smaller than the disks F a sufficient extent of rotation of the disks to bring any one of the type characters thereof (which occupy about one-half of the periphery of each disk) to the printing-line is afforded with a movement of the lever G, permitted within the limits imposed by reason of the construction of the device.

The grooves of the front curved plate C of the type-disk chamber are provided with a plurality of notches c', into which the handle G² of the levers springs to hold the levers stationary, and said front plate is also provided with one or more scales (indicated at c²) composed of characters identical with and arranged in the same manner as those on the peripheries of the disks, whereby when the handle G² of a lever is in line with either of said characters of the scale the same character of the disk operated by said lever is at the printing-line at the top of the machine. Preferably a number of scales will be provided on the front wall of the machine equal to the number of the slots c, so that there will be a scale adjacent to each slot.

In order to hold the disks steady during the time an impression is being taken from the type in the printing-line, said disks are herein shown as provided in the parts of their peripheries not occupied by the series of characters with a plurality of shallow V-shaped notches f³, (shown best in Fig. 3,) which engage correspondingly-shaped teeth or projections i of leaf-springs I, that are attached at their forward ends to a transverse rod I' and preferably bear at their rear ends against the inner curved face of the back wall of the chamber. Said springs need not possess great strength, and therefore do not tend to add appreciably to the power required to rotate the disks. So far as is concerned the combination of the levers G with the disks F, the printing device may embody one or more sets of such mechanism, as desired.

Any suitable form of platen may be employed, which of course will be of a length at least as great as that of the slot d, at which the printing-line is set up. The platen herein shown consists of a flat horizontal plate or bar J, located above the plate D, and is provided with a centrally-attached stem J', which has guiding engagement with the head A² and is provided at its top with a disk j, which is adapted for contact with the eccentric head a of a swinging lever A³. Springs

a' act to hold the platen in its uppermost position, and the platen is depressed by means of the lever A³. As herein shown, a ribbon K is interposed between the platen and the type, said ribbon being wound at its ends 70 around spools K' K', carried by the ends of said plate or bar J. The platen is preferably provided above the ribbon with a yielding cushion K², which is shown in Fig. 4.

In order to limit the throw of the lever A³, 75 and thereby modify the extent of the depression of the platen, and therefore the impression produced on the check or the like, I have shown a suitable adjusting-screw L, that is inserted through the head A² and engages at 80 its inner end a suitable notch a² in the eccentric head of the lever A³, as shown best in Figs. 3 and 4. By turning said screw L inwardly the depression of the platen is limited, and therefore the impression on the check or 85 document at the set-up printing-line is less than when the swing of the lever A³ is greater, which latter may be accomplished by turning the regulating-screw L outwardly.

A gage-bar M is employed to properly register the checks with the printing-line. Said gage-bar is slotted and is attached to the top plate D of the printing-disk chamber by means of screws m, which extend through the longitudinal slots of the gage-bar and also 95 through transverse slots d² in the top wall or plate D, whereby the gage-bar may be shifted both forwardly and backwardly and also laterally with respect to the top plate. The gage-bar is provided with end stops M' M', 100 engaging the end of the check or document to register the impression in proper longitudinal position on the check or the like.

In the operation of marking a check by the use of my improved marker the check is inserted between the printing-line formed by the characters at the upper sides of the disk and ribbon, and the platen is then depressed. The check or other document being interposed between the ribbon and the types, the 110 said types are not subjected to the corrosive action of the ink, nor will the types be filled by ink, such as would occur if the types were brought into contact with said ribbon. The presence of the yielding cushion K² permits the types to pass upwardly into the check, and thereby emboss the same. As a result the check or other document is embossed from beneath and the ink impression of the ribbon is applied on the relief-faces of 115 said embossed characters.

I claim as my invention—

1. The combination with a rotative disk provided on its periphery with a series of types, of a shaft on which it is rotatively 125 mounted, a gear-pinion fixed concentrically on the flat face of the disk, a lever pivoted at its rear end to a part stationary with the shaft and provided between its ends with a curved slot within which the said gear-pinion ex- 130

tends, one margin of the curved slot having a curved rack concentric with the pivot of the lever which meshes with said gear-pinion.

2. A check-marking device embracing a fixed frame provided with a chamber, a shaft extending therethrough, a plurality of character-disks mounted side by side and independently rotative on said shaft, each disk being provided on its periphery with a series of types, said frame being provided in its top wall with an opening through which the types of the disks project to constitute the printing-line and in its front wall with a plurality of slots, a reciprocating platen for pressing the work against the types, pinions affixed concentrically to and rotative with said disks, levers interposed between the type-disks and hinged to the frame and provided with curved gears meshing with said pinions of the disks, and with handles extending forwardly through said slots in the front wall of the chamber.

3. A check-marking device embracing a frame provided with a chamber, a shaft extending therethrough, a plurality of character-disks mounted side by side and independently rotative on said shaft, each provided on its periphery with a series of types, said frame being provided in its wall with an opening through which the types of the disks project to constitute the printing-line, and in its front wall with a plurality of slots, pinions affixed concentrically to and rotative with said disks, levers located between said disks and hinged at their rear ends to the frame of the machine, said levers being provided with handles which extend through said slots in the front wall of the frame, and between their ends with curved slots, the side margins of which are formed to constitute gears which mesh with the pinions of the associated type-disks.

4. A check-marking device embracing a frame provided with a chamber, a shaft extending theracross, a plurality of type-disks rotatively mounted and independently rotative on said shaft, each provided on its periphery with a series of character-types, and on their sides with concentric pinions, said frame being provided in its wall with an opening through which the types of the disks project to constitute the printing-line, and in its front wall with a plurality of slots, levers located between said disks and hinged at their rear ends to the frame and provided with

handles which extend forwardly through said slots in the front wall and provided between their ends with curved slots having their side margins formed to constitute curved racks which mesh with the gear-pinions of the type- 60

5. A check-marking device embracing a frame provided with a chamber, a shaft extending thereacross, a plurality of type-disks rotatively mounted and independently rotative on said shaft, each provided on its periphery with a series of character-types, said frame being provided in its wall with an opening through which the types of the disks project to constitute the printing-line, and in its front wall with a plurality of slots, levers located between said disks and hinged at their rear ends to the frame and provided at their front ends with handles which extend forwardly through said slots in the front wall, 75 and provided between their ends with curved slots on one margin of which are formed curved racks which mesh with the gear-pinions of the type-disks, said disks being provided on the parts of their margins not occupied by the type-spaces with V-shaped notches, and a plurality of springs one for each disk provided with projections adapted to engage said notches.

6. A check-marking device comprising a frame provided with a chamber, a shaft extending thereacross, a plurality of type-disks rotatively mounted and independently rotative on the shaft, said disks being provided with concentric gear-wheels which turn there- 90 with and interposed between the disks, levers interposed between the disks and pivoted at their rear ends to the frame, said levers being provided with curved slots into which said pinions extend, and provided with curved gear-teeth which mesh with the pinions, said levers being provided with forwardly-extending handles which extend through slots in the front wall of the casing, the front wall of the casing being provided 100 with scales.

In testimony that I claim the foregoing as my invention I affix my signature, in presence of two witnesses, this 9th day of August, A. D. 1904.

LOUIS SMITH.
